UNITED STATES PATENT OFFICE.

FRED T. LANE, OF SPOKANE, WASHINGTON.

VALVE.

Application filed March 5, 1926. Serial No. 92,550.

My invention relates generally to improvements in valves and more particularly to improvements in valves of that class to which safety valves belong, and it consists in 5 the combinations, constructions and arrangements herein described and claimed.

An object of the invention is the provision of a valve of the character described which is adapted to open automatically when the 10 pressure at the inlet of the valve reaches a predetermined pressure, which may vary at will within a considerable range, and which includes a valve which will be held against its seat when the pressure at the inlet is 15 lower than said predetermined pressure without the use of the usual weights for preventing opening of the valve at a pressure lower than said predetermined pressure.

A further object of the invention is the 20 provision of a valve of the character described which includes manually operable means for opening the valve when desired.

A still further object of the invention is the provision of a valve of the character described having yieldable means functioning to hold the valve closed and having also means for adjusting said yieldable valve closing means so that the valve will open at any 25 predetermined pressure within a consider- 30 able range, the invention also contemplating the provision of indicating means adapted to be actuated by the adjusting means for indicating on an associated scale the particular pressure at which the valve will open at a 35 given time.

Other objects and advantages of the invention will be apparent from the following description, considered in conjunction with the accompanying drawings, in which—

40 Figure 1 is a side elevation of the improved valve.

Figure 2 is a vertical section through the improved valve, the view being at right angles to Figure 1,

45 Figure 3 is a horizontal section substantially along the line 3—3 of Figure 2.

The casing of the improved valve comprises a tubular body section 1 which may be vertically disposed as shown in Figures 50 1 and 2. The body 1 is formed with a lateral tubular outlet 2 adjacent to its lower end and is enlarged internally for a short distance upward from the level of the lower part of the bore of the tubular outlet 2, as indicated at 3. An upwardly facing shoulder 4 thus is produced at the bottom of the

enlargement 3 and this shoulder 4 is mar- 5 gined at its inner edge by an upwardly ex- tending tapering circular rib or ridge 5. The body 1 also is reduced internally below 60 the shoulder 4 at 6, thus producing a down- wardly facing shoulder 7 against which a screen 8 is disposed and secured in place in any suitable known manner. The lower end portion of the body 1 is provided below the shoulder 7 with internal screw threads for engagement at 9 with a supply pipe 10 for conducting fluid pressure to the valve casing. The lower end portion of the body 1 below the shoulder 4 therefore constitutes an inlet 70 and the upwardly extending ridge 5 is a valve seat, as will presently appear. The portion of the bore of the body 1 above the enlargement 3 is circular in cross section. The casing of the body also includes a tubu- 75 lar head section 11 having an externally re- duced lower end portion 12 which is in threaded engagement at 13 with the upper end portion of the body section 1 of the valve casing. The upper end portion of the bore 80 of the head section 11 is enlarged internally at 14 for the reception of packing rings 15 which may be compressed against the bot- 85 tom of the enlarged portion 14 by a follower 16. Pressure is exerted on the follower 16 by a screw cap 17 which is screwed onto the upper end portion of the head section 11 of the valve casing. A gasket 18 may be dis- 90 posed on the reduced lower end portion 12 of the head of the valve casing between the upper end of the body section 1 and the ad- 95 jacent portion of the head section 11.

A valve block 19 of circular cross sectional configuration is provided for controlling flow through the inlet of the valve casing 100 into the internally enlarged portion 3 of the valve casing. The valve block 19 has a body made of relatively hard metal, such as tool steel, formed with a socket 20 in its lower face of greater diameter than the diameter 105 of the outer wall of the valve seat 5. This socket 20 is filled with a softer metal such as babbitt, as indicated at 21, level with the lower face of the valve block body, whereby the lower or contact face of the valve block 19 will be flat. The upper edge of the valve seat 5 lies in the same plane throughout its circumference and the valve block 19 therefore will rest flatly on the valve seat 5, thus 110 positively preventing escape of pressure fluid from the inlet of the valve casing into the internally enlarged portion 3 of the valve cas-

ing when the valve block 19 is held firmly in place on the valve seat 5.

The valve block 19 also is formed with a socket 22 in its upper end for the reception

5 of the lower end portion of a relatively heavy and strong expansion spring 23, the upper end portion of which bears against an adapted disk 50 which is disposed between the flat lower face of the enlarged lower end 10 portion 24 of a valve stem 25 and the upper end of the spring. The upper end portion of the spring encircles a central retained projection 51 on the lower face of the disk 50. The stem 25 extends through the head section 15

11 of the valve casing and is provided above the enlargement 24 with external screw threads 26 for engaging with internal screw threads 27 on the internally reduced lower end portion 12 of the head section 11.

20 A lifter sleeve 28 is slidably and rotatably disposed in the bore of the body section 1 of the valve casing above the level of the lower or bottom wall of the enlargement 3 of the bore of the body section of the 25 valve casing and above the level of the bottom wall of the valve block 19. The upper end portion of the lifter sleeve 28 is secured to the enlarged lower end portion 24 of the valve stem by a cross pin 29. The 30 lifter sleeve 28 carries a pair of inwardly extending diametrically opposite projections 30 which may be the shanks of set screws 31 which screw in the threaded openings in the lifter sleeve. The projections 30 extend into 35 a circumferentially extending groove 32 in the outer wall of the lifter sleeve 28 and the diameter of each of the projections 30 is considerably less than the width of the groove 32. The portion of the lifter sleeve 40 which depends below the level of the upper wall of the internal enlargement 3 of the body section 1 of the valve casing may be formed with a plurality of circumferentially spaced radial apertures 33.

45 The valve stem 25 extends through the packing rings 15, the follower 16 and through a central opening in the crown portion of the cap 17 above the level of the latter. A collar 34 is removably and adjustably secured in place on the valve stem 25 above the cap 17 by means of a set screw 35. The collar 34 carries an indicator arm or pointer 36 which as best seen in Figure 2 and is of sufficient length to terminate at its 55 lower end close to the face of a strip 37 which is secured by screws 38 to the upper end portion of the body section 1 of the valve casing. The strip 37 has a scale 39 produced thereon, the graduations of which 60 are marked to indicate in pounds different pressures at which the valve block 19 will move upwardly from its seat and from position to cover the inlet of the valve casing. The pressure which will be sufficient to force 65 the valve block 19 upwardly from its seat

against the action of the spring 23 of course will vary according to the extent of compression of the spring 23 by the valve stem 25.

A hand wheel 40 for turning the valve 70 stem 25 is removably secured in place on the extreme upper end portion of the valve stem by means of a retaining nut 41.

The lateral tubular extension 2, which constitutes the outlet of the valve casing, 75 may be provided with internal screw threads for engagement at 42 with a discharge pipe 43.

From the foregoing description of the 80 various parts of the device, the operation thereof may be readily understood. The screen 8 will prevent passage of particles of dirt and like matter with the pressure fluid against the bottom of the valve block 19 and thus will prevent any such particles 85 from lodging between the contact face of the valve block 19 and the valve seat 5. The collar 34 is secured in place on the valve stem so that the indicator or pointer 36 will point to 0 on the scale strip 37 when 90 the spring 23 is fully expanded or uncompresed position. Turning of the valve stem 25 in a clockwise direction then will cause compression of the spring 23 against the valve block and the indicator 36 will 95 move simultaneously along the scale strip 37 and will at any given time indicate in pounds the pressure which will be required to force the valve block 19 from its seat 100 against the action of the spring 23. The lifter sleeve 28 will turn with the valve stem and the projections 30 will move downwardly toward the bottom of the groove 32 as the valve stem is turned in the direction required to compress the spring 23. The 105 valve block 19 does not rotate, however, but remains firmly in place against the valve seat as a result of the action of the spring 23 until the pressure against the valve block 110 19 is sufficient to cause the latter to move upwardly from its seat against the action of the spring 23. In the event that it is desired to compress the spring 23 to an extent greater than would be possible with the particular pressure transmitting adapter disk 50 shown in the drawings and the particular groove 32 and the projections 30 shown in drawing, a similar pressure transmitting adapter disk 50 of greater thickness may be substituted for the particular 115 adapter disk shown in the drawings and the valve block closing means thus adapted to hold the valve block 19 against its seat a higher pressure than could have been resisted before the substitution of the relatively thick adapter disk for the particular adapter disk shown in the drawing.

120 When it is desired to open the valve as a result of manual action, the valve stem is rotated in a counter clockwise direction,

first relieving the spring 23 of compression and then causing the projections 30 to engage with the upper wall of the groove 32 and to then lift the valve block 19 upwardly from its seat. The valve block thus can be held from its seat when desired and as soon as the stem 25 has been turned in a clockwise direction as required to compress the spring 23, the latter will function to force the valve block 19 downwardly against the valve seat 5 and will firmly hold the valve block in place until the pressure of the fluid which impinges against the bottom of the valve block is sufficient to overcome the resistance of the spring. The pressure fluid which passes into the internally enlarged portion 3 of the valve casing when the valve block is in open position will circulate about the lower end portion 23 of the lifter sleeve 28 and the lower end portion of the valve block and will keep the adjacent surfaces of such parts clean, some of the pressure fluid passing through the apertures 33 in the lower end portion of the lifter sleeve as soon as the valve block 19 has been moved outwardly below the level of the lower portions of the apertures 33. The upper end portion of the valve casing may be termed a stuffing box.

Obviously, my invention is susceptible of embodiment in forms other than that illustrated in the accompanying drawings and I therefore consider as my own all such modifications and adaptations of the form of the device herein described as fairly fall within the scope of the appended claim.

I claim:—

A valve comprising a casing having an inlet at one end and having a lateral outlet adjacent to said inlet, said valve casing being formed to produce an inwardly extending valve seat at the inner end of the inlet, a valve block slideable in the valve casing to and from position to bear against said valve seat and to then close said inlet, a valve stem extending from the opposite end of said valve casing and having a portion in threaded engagement with the adjacent end portion of the valve casing, the inner end portion of said valve stem being enlarged, a thrust imparting adapter disk movable within the valve casing and being disposed against the inner end of said valve stem, an expansion spring between said adapter disk and said valve block, a lifter sleeve disposed within said valve casing in encircling relation to said valve block, said lifter sleeve being capable of axial and rotary movement in the valve casing, means connecting the upper end portion of said lifter sleeve with the valve stem, said valve block having a circumferentially extending groove in its outer face, and a projection carried by said lifter sleeve and extending into said groove, the end portion of said lifter sleeve nearest to said inlet having radial apertures for the circulation of fluid therethrough when said valve block has been moved in the lifter sleeve away from its seat.
